UNITED STATES PATENT OFFICE.

GEORGE C. WING AND LOUIS P. LIPPS, OF CLEVELAND, OHIO, ASSIGNEES TO SAID
WING, TRUSTEE.

STREET-CAR AND SIMILAR VEHICLE.

1,142,867.

Specification of Letters Patent. Patented June 15, 1915.

Application filed December 21, 1914. Serial No. 878,374.

To all whom it may concern:

Be it known that we, GEORGE C. WING, and LOUIS P. LIPPS, both citizens of the United States, residing in the city of Cleveland, in the county of Cuyahoga and State of Ohio, have together invented a new and useful Improvement in Street-Cars and Similar Vehicles, of which a full, clear, and exact description, wherein reference is made 10 to drawings that accompany and are to be considered as a part of the specifications, is hereinafter set forth as follows.

Our invention applies to, and is more immediately concerned with the requirements 15 of car service, on surface, supersurface or subsurface roads, in and about modern cities or large popular centers, where traffic congestion occurs, and is to be relieved, either occasionally, as to or from theaters, ball- 20 games, race-tracks, fairs or other exhibition or amusement points, gathering places and attractions, or, regularly, at certain periods as is invariably the case during the rush hours, when the great offices, workshops, and 25 business houses are opening or closing for the day.

On these occasions, the first demand is not so much with respect to the manner and comfort, as the promptness and speed with 30 which passengers are handled, for few there are at these times, who do not prefer to stand in a car, and meanwhile be carried toward their destination, than to stand on a sidewalk until a car with vacant seats arrives. It results that during rush hours 35 the only limit to the passenger capacity of a car is the accessible foot-space therein and no inconvenience or discomfort is enough to bar the full occupancy of such space. It 40 will accordingly be found that the greater number of passengers in a loaded car never have seats at all, or, indeed, never enter a car with the expectation of gaining seats. On these occasions, therefore, the standing 45 passengers compose, as they ever will, a distinct and major portion of the great body of car-riders and a proper regard for their interest should therefore prompt car operators to make use of the best attainable 50 means, under the circumstances, for lessening the discomforts and increasing the safety of this class from the moment of embarkation until their journey ends. As a matter of fact, however, there has been a 55 singular indifference or lack of resourceful-

ness and enterprise, in the connection, on the part of car-designers, car-buyers and car-operators, inasmuch as the only provision heretofore made to improve the condition of this large class of their patrons, has 60 taken the form of overhead supports, like horizontal poles, or the familiar straps, inherited from the slow-moving horse-cars, or latterly, the occasional and somewhat precarious stanchions between the floor and 65 ceiling of the car, to and around which a few of the many aisle inhabitants are allowed to cling and swing as they ride. Any overhead support, however, like straps, loops or horizontal poles necessarily falls 70 far short of the requirements of the situation, since only the tallest of the standing passengers can reach and use them, and, then without obtaining any firm hold against being swayed and moved from their 75 places by the crowd at each lurch of the car. Most women, and all persons below the average height, cannot use such supports at all. Furthermore, the constant physical effort required of one, in the process of strap-hanging, and the consequent fatigue, is by 80 no means ignorable, nor, also the menace to his neighbors from the umbrella or package of the one so engaged, when, as is often necessary, these articles are grasped by the 85 same hand which has hold of the strap or pole. Stanchions at intervals along the seats, are only effective radially from their upright line, and, being without other than vertical extension, they can give, in themselves, but inadequate protection against the shocks from the starting or stopping, and the pressure of the mass around. A passenger between or near a stanchion, if 90 taken unawares by the sudden movement of the car, is also liable to be bumped or violently thrown against the same, and seriously injured. The prevailing aids to standing passengers are thus unscientific and insufficient for the purpose. 95

March 29th, and August 2nd, 1910, respectively, by United States Patents 953502 and 965972, plans were duly disclosed to meet and measurably remedy the very exigencies under consideration. These plans, 105 in brief, were to arrange transverse handrests, at intervals, throughout the floor of a car, at proper distances apart, to admit standing passengers between and in close reach of the same, and at suitable heights 110

from the floor to be conveniently grasped. The main idea was to divide up, in this manner, the mass of standing passengers, into small units within the several quasi compartments, thereby segregating each unit from the rest, and insuring each individual member of such units, at the same time, a place from which he could not be crowded, and, a firm and natural support during the ride.

The ideas, thus presented, somewhat emphasized the possibility of doing away with a certain number of seats in the connection, and did not disclose any definite form or application of the invention, wherein the fullest possible advantages of the same would be realized without, in the least, encroaching upon the seat space of a car, or reducing, at all, the number of seats now used.

The main purpose of the present invention, therefore, is to supplement the ideas already broadly presented with particular forms and arrangements pertinent, so as to completely accomplish the ideas last above referred to, and bring about that, in the end, a vehicle shall be realized which, with other advantages, shall have and preserve intact the accepted maximum capacity for both seated and standing passengers.

In the accompanying drawings, Figures 1 to 5 are diagrammatic plans of car floors where the floor space, seats, and said handrests, are variously arranged, in relation to each other, according to the invention now under consideration. Fig. 6 is a cross vertical section of a car, with a side view of one form of a handrest in its place therein relatively to floor space, and longitudinal seats (shown in section) at the sides of the car, corresponding, in their correlations in the several respects, with the arrangements indicated in Figs. 1, 3, and 5. Fig. 7 is a similar view of said elements, when the handrest itself is combined with a stanchion located immediately in front of a longitudinal seat, and the seats opposite are single, and arranged in tandem, as shown in Fig. 4, and, Fig. 8 is a like view when the handrests severally extend above the back of cross seats to the median line of the car, and the seat, on the opposite side of the car, is longitudinal thereof, as illustrated in Fig. 2.

Explaining the several arrangements in their order, C is the car as a whole, which with its different parts, is drawn to a scale in the figures, and represents, in most of the same, in respect to dimensions, seats and doors, various forms of cars which have been actually used.

Figs. 1 and 2 show cars of the rear-entrance pay-enter type; Figs. 3 and 4, cars of the side-entrance pay-enter or leave type, and Fig. 5, a recently constructed front-

entrance, side-exit, center-payment car, in connection with which the present invention, for many reasons, will be found to be especially appropriate and useful.

The plan of car shown in Fig. 1 is a familiar one in its main features. The fare box F is located centrally of the back platform P, with the exit and entrance doors E at the side of the same. Interiorly, there are longitudinal seats, or benches, S, S, at each side of the car with an interspace, of maximum dimensions, for standing passengers. In ordinary cars the normal aisle, or passageway for the movement of passengers to and from the ends of the car, is midway of such space. The seating capacity of said car, as is indicated, is twenty-four along each side. In prevailing cars of this type, continuous rods or individual straps, for the support of standing passengers, are located immediately above said seats. Our improvement, over this type, consists in establishing the aisle M, not midway of such space, as in the ordinary forms of car, but slightly off or immediately adjoining the center line of the same, and then, omitting all overhead supports on the side farthest from the aisle, and, substituting, in their place, or merging their functions in, a series of rigid, ballustrade-like horizontal handrests D which extend, at intervals, between the aisle across the space on said side to said seat. Said handrests are parallel with each other, and should be at suitable distances apart to admit, to the floor-space, or section between adjoining members of the series, the full complement of standing passengers to which such section is entitled, and, at the same time, under such conditions, that each of said passengers will be within easy reach of one or the other of the handrest barriers D of his particular section. Said handrests should be of a proper height from the floor to be conveniently grasped by the passengers when standing near the same. Any form of overhead handrests desired, for the other side of the aisle, may, of course, be provided, to serve passengers who cannot avail themselves of the handrests described. In the figures such an overhead support is denoted by T. The precise form of the handrests D is not of the essence of the invention, except when derived as indicated in Fig. 7. When employed in front of longitudinal benches, they may consist of straight horizontal bars supported near their aisle-end by straight or inwardly curving posts or vertical rods, which latter may be integral pieces or otherwise, and may pass over the seat to the wall of the car at the other end, or simply terminate with such ends resting upon the seat itself. In Fig. 7, we show a special mode of making up and locating said handrests D, when used in connection with long side seats and an off-

center aisle M, as stated, which has peculiar merits as compared with other forms of this feature, or element of the combination, and, is accordingly made the subject of specific claims herein, as a modification of the broader idea disclosed in Fig. 1. It consists of the combination of the horizontal bar- 5 portions of the handrests D, directly with stanchions I arranged along the front of the seats at predetermined intervals. In this 10 relation, said bars are fastened at right angles to the stanchions and, preferably, are of no greater length than is requisite to span the distance between the stanchions 15 and the determined location, in each case, of the aisle M (Fig. 7).

It will be apparent, at once, that, in this 20 arrangement, besides securing a firm support for the inner end of the transverse portions of the handrests D, the racking leverage on that portion is greatly reduced, as compared to the form when such portion is carried back over the seats to its place of fastening. The horizontally extending arms 25 of D, in this manner, will amply guard passengers from being unduly thrown against the stanchions, as is the danger when the latter are used alone. The combination has the further advantage that it can be installed without intruding upon, or being 30 within the seat-space which latter is left entirely free and clear, without liability of any part of the installation encountering the head-gear, or person of the seated passengers. At the same time, said special form 35 will also serve to distinctly space off the longitudinal seat in its rear so that standing passengers will readily see when their more fortunate neighbors are occupying a greater 40 portion of the seat than is their share, and will be at liberty to invite them accordingly to sit closer and make room on the seat for one more.

Although, in said combination, the primary service of the stanchions is not as a 45 support for standing passengers, nevertheless, such service, to a certain degree, will still be performed by them. In addition, in such connection, they will be at hand to afford first aid to a passenger as he is rising 50 from his seat on his way out between the handrests to the aisle.

At this point, it may be observed, that the general plan of locating divisional compartments of the maximum capacity for standing passengers, and from which they cannot be crowded out by their follow-passengers, gives each tenant of such compartments a fixed place within, and operates, in 55 fact, as a truly democratic measure to insure uniform and fair treatment to all concerned. The passengers who have once gained a standing place within a given compartment, between the two adjacent handrests D, have 60 thereby acquired a vested and unquestioned

right, so to speak, to any and all vacancies, as they occur, at that portion of the long seat S against which their own compartment abuts. When, therefore, a vacancy does occur, those within the compartment have the right 70 of way to the same, in the order of their propinquity and without the possibility—as in ordinary cars—of being elbowed away from their chance. The free for all race for seats, which is a conspicuous and unpleasant 75 feature of modern rush-hour travel, will thus be entirely eliminated, and, with the disappearance of the crowding and commotions incident thereto, passengers at large, will be relieved, to a corresponding degree, of what 80 is now a constant source of irritation and discomfort.

The arrangement shown in Fig. 2 preserves a full complement of seats, but, by their character and arrangement, brings about a 85 marked coercive effect with the aisle and the transverse supports on the cross-seats at their side of the car. Of course, the full value of the arrangement calls for either a longitudinal bench on the opposite side of 90 the car and aisle, or—which would be an ideal plan—the substitution, on that side, in place of the longitudinal bench S, of single seats S² arranged in tandem, or, fronting 95 lengthwise of the car, in the manner appearing in Fig. 4. The handrests D, in Fig. 2, as is evident, extend to the medium line of the car's floor, and, may, themselves, be severally attached to and supported by the backs B, of the cross-seats S¹, in any suitable 100 manner.

Figs. 3 and 4 represent a type of center-entrance motor-car, having the off-center aisle M in each compartment, or half, of the car, and the series of handrests D, which 105 extend from or over the longitudinal benches S to said aisle, alternately located, with respect to each other, in said halves.

Such alternate locations serve to balance the load, and to form indirectly the shortest 110 pathway around the box, for fare depositors from one end of the car, and to the exit doors for passengers from the other end. Fig. 4 only differs from the design in Fig. 3, in having single seats S² arranged in tandem, as has already been pointed out. This latter feature, by locating the foot-space 115 for seated passengers between the cross-seats, of course, makes available for standing passengers a corresponding space in the 120 aisles M, and, insures those who occupy the cross-seats from any close contact with those who stand.

Inasmuch as the chief employment, as originally designed, for a car according to 125 the plan in Fig. 5, is on branch and short-haul lines, where the propriety, or even wish for seats, is of little importance in the minds of the car-riders, the desirability of carrying and caring for as many standing pas- 130

sengers upon the vestibule or entrance half of the car as possible, is much emphasized. In this type, passengers only enter the car at E¹, and leave at E², depositing their fares in the box at P, whenever they pass that point, either to ride in the rear half of the car, or to depart at E². No one who is to ride but a few blocks will care enough for a seat to go farther than the compartment or front half of the car he first enters, but does require the best and most adequate facilities for standing that can be afforded.

Such facilities, we insist, are best found, in the connection, in the employment of the general system of parallel handrests referred to herein, but, only, to the fullest degree, when the aisles are located either wholly, or for the most part, off the center line of the floor along and adjoining the seats on that side of the car, and said system installed on the floor space between the aisle and the seats on the other side of the car. The cross dimension of car floors is so limited, that, when the aisle is located along the center, and the handrests at both sides thereof, such handrests will not project far enough from the seats, to hold between the several pairs a number of persons that is sufficiently proportionate to the increased number that can be so received and supported when the handrests are extended to the middle of the car on one side. Only by shifting the aisle and thereby appreciably enlarging the space between said supports, can the fullest advantage of the latter be realized. The application, therefore, of our present ideas to a car, like that shown in Fig. 5, where long trips are not to be made, is especially appropriate. Indeed, in said car, it would be a further improvement, under the circumstances, and one which would doubtless be welcomed by all passengers in the same, if our off-center aisle, and unilateral installment of handrests, were supplemented by the entire removal of the seats, in the front end of such car, along the side of the car where the handrests themselves are located.

Having thus fully described our invention and set forth concrete embodiments of the same, what we claim and wish to protect by Letters Patent is:—

1. In a street car, or similar vehicle, the combination of a longitudinal seat at one side of the same, an off-center aisle, or passageway, along and adjoining said seat, a longitudinal seat at the other side of the car opposite to the seat first above named, and

horizontal hand-rests for standing passengers, at intervals, above and across the floor space between said aisle, or passageway, and the longitudinal seat, last above named, on the other side of the car, substantially as shown and described. 60

2. In a street car, or similar vehicle having oppositely located longitudinal seats at the sides thereof, the combination of an off-center aisle, or passageway, along and adjoining such seat on one side of the car, and horizontal handrests for standing passengers, at intervals, above and transversely of the floor space between said aisle or passageway, and the seat on the other side of the car opposite to the first seat hereinbefore specified, substantially as shown and described. 70

3. In a street car, or similar vehicle, the combination of oppositely arranged longitudinal seats at the sides thereof, and a series of parallel handrests for standing passengers, extending transversely through the space between one of said seats and the middle of the car, substantially as shown and described. 80

4. In a street car, or similar vehicle, having oppositely located longitudinal seats at the sides thereof, the combination of an off-center aisle, or passageway along such seat on one side of the car, and horizontal handrests for standing passengers, at intervals, above and transversely of the floor space between said aisle and the seat on the opposite side of the car, substantially as shown and described. 85

5. In a street car, or similar vehicle, the combination of a longitudinal seat at the side thereof, a stanchion, in front of and adjacent to the same, and, a bar, or handgrasp for standing passengers, affixed at one end to said stanchion, and extending outwardly therefrom to the middle of the car, substantially as shown and described. 95

6. In a street car, or similar vehicle, the combination of a longitudinal seat at the side, a series of stanchions, in front of and adjacent to said seat and bars or handgrasps for standing passengers, severally fastened to the stanchions, at one end, and extending outwardly therefrom to the middle of the car, substantially as shown and described. 105
